GAS LIFT PUMPING APPARATUS

Jan Lambertus Benard, Southwell, England

Application February 3, 1944, Serial No. 520,887
In Great Britain November 24, 1942

8 Claims. (Cl. 103—231)

The invention relates to gas-lift pumping apparatus for raising liquids to an elevated delivery point.

The invention has among its objects automatically and intermittently to admit into a displacement chamber charged with the liquid to be raised, equal volumes of gas or air under pressure under similar operating conditions without regard to the timing of the intervals, and without affecting the pressure conditions in the pressure gas supply system during the operation.

A further object of the invention is to use small diameter pressure-gas supply lines, while avoiding the use of gas reservoirs or capacity headers, which are necessary in the use of mechanically operated timing devices for smoothing out the pressure drop in the pressure supply lines during the operation.

A further object of the invention is to avoid the use of timing devices and control stations that are liable to get out of order and thereby cause production losses.

A further object of the invention in its application to oil wells is to avoid exhausting into the casing of the well, part of the operating pressure-gas admitted into the displacement chamber, and fully to utilise the energy available in the pressure-gas to raise to the delivery point the liquid charged into the displacement chamber.

A further object of the invention is to provide means for raising the liquid from small producing, or "stripper" wells by means of gas supplied from the casingheads of wells producing quantities of gas, against a determined back-pressure without affecting the back-pressure conditions of the wells supplying the gas.

A further object of the invention is to provide means for raising a maximum quantity of liquid with a minimum practicable quantity of pressure-gas.

According to the invention pressure gas at consecutive intervals and in controlled quantity is intermittently charged into a closed pressure-gas space or receptacle to a determined operating pressure, the pressure-gas space or receptacle being disposed in position above and in fluid tight relation with the liquid displacement receptacle charged with the liquid from an outside source such as an oil well, whereby the liquid is held within the liquid displacement receptacle, the lower part of the rising main being disposed within the pressure-gas receptacle and being equipped with automatically operating mechanism comprising a pilot valve, a piston device and a pressure-gas inlet valve, the pilot valve being

adapted to be opened under the pressure of gas derived from the pressure-gas space or receptacle, on the operating pressure therein being attained, whereby on the pilot valve being thus opened for the admission of the pressure gas to the cylinder of the piston device, the latter operates to open the pressure-gas inlet valve to admit into the upper part of the liquid displacement receptacle, pressure gas derived from the pressure-gas space or receptacle, thus raising the liquid through an eduction pipe extending downward into the liquid displacement receptacle, and thence through eduction conduits within the lower part of the rising main and through the main to the delivery point.

The invention while of particular application to oil wells, is of general application in pumping liquids to an elevated delivery point in such an intermittently operating gas-lift pumping apparatus.

The invention is hereinafter described with reference to the accompanying drawings, in which:

Figure 1 is a diagrammatic vertical section of apparatus provided for raising liquid, oil or water from an oil well.

Figure 2 similarly illustrates the valve operating mechanism on a slightly larger scale than in Figure 1.

Figures 3a, 3b and 3c are partial views of a construction of apparatus similar to that illustrated diagrammatically in Figure 2 and together present a substantially complete vertical section of the apparatus on a larger scale.

Figure 3a shows the upper part, Figure 3b the middle part and Figure 3c the lower part of an apparatus generally corresponding with the respective upper, middle and lower parts of the apparatus diagrammatically represented in Figure 2 separated on the lines a—a and b—b indicated in that figure.

Figures 4 to 9 illustrate the housing of the main gas-inlet valve employed in the construction illustrated in Figures 3b and 3c, in which,

Figure 4 is a vertical section of the line d—d (Figure 5) of the main gas-inlet valve housing shown in the lower part of Figure 3b and in the upper part of Figure 3c.

Figure 5 is a sectional plan on the line a—a (Figure 4).

Figure 6 is a vertical section of the main gas-inlet valve housing on the line e—e (Figure 5).

Figure 7 is a sectional plan on the line b—b (Figure 6).

Figure 8 is a vertical section on the line *f-f* (Figure 5).

Figure 9 is a sectional plan on the line *c-c* (Figure 8).

Figure 10 is a vertical section of the main gas-inlet valve seating sleeve.

Figures 11 and 12 are respectively a sectional elevation on the line *a-a* (Figure 12), and a corresponding plan of the pilot valve housing shown in the construction of Figure 3b.

In carrying the invention into effect according to one construction diagrammatically illustrated in Figures 1 and 2 of the accompanying drawings, the casing 2 of the oil well, that may as usual comprise a number of connected length sections of the casing, is provided at its lower end with a perforated part 3. Suspended within the casing 2 is a tubing string 4 serving as the external wall of the pressure-gas receptacle, the tubing string comprising, as usual a number of connected tube length sections, having at the lower end an enlarged and advantageously cylindrical receptacle forming a liquid displacement chamber 5. At the bottom of the liquid displacement receptacle 5 is an inwardly opening check valve 7, which permits the oil or the liquid at the bottom of the well or bore-hole to enter and to accumulate in the liquid displacement receptacle 5, but prevents the return of gas or fluid into the casing or bore-hole or the operating pressure gas exerting an excessive pressure on the bore-hole or well formation.

Above the liquid displacement receptacle 5 and in the tubing string 4 a conical seat 6 is provided upon which the lower part of the rising main or casing 8 enclosing the automatically operating valve mechanism is supported, the casing 8 serving as an eduction conduit or lower part of the rising main through which the liquid passes upwardly. Extending downwards through the tubing 4 is the casing 9 and the rising main 8, the lower end of which is connected to or integral with the upper end of the casing 9. A gas-tight seal is thus maintained at the conical seat 6 of the lower end of the casing in the use of the interposed lead ring 10. Beneath the casing 9 the eduction pipe 11 of a small bore extends downward, and may reach a position immediately above the inwardly opening check valve 7.

The automatically operating valve mechanism of the gas lift displacement pump apparatus as illustrated in Figure 2 consists of the casing 9 provided near its lower end with a gas inlet valve housing 20 within which a mushroom pressure-gas inlet valve 17 is mounted. The valve 17 has an upwardly extending valve stem 21 on which a guide 22 is mounted, which maintains the valve 17 and valve stem 21 centrally in the bore 18. The valve 17 has a downwardly extending valve stem 24 which freely moves in a bore 25 in the valve housing 20. The valve 17 is pressed upward into close contact with its seat 27 by means of a helical spring 26, and also by pressure of the gas which enters below the valve 17, through the port 28 in communication with the annular pressure space 13.

In the gas-inlet valve housing 20 a port 29 is provided which communicates at its lower end with the liquid displacement receptacle 5, and through the bore 18 with the casing 9. The port 30 provides communication between the eduction pipe 11, and the space 9c, and the valve body 20 has at the upper end of the bore 18 a conical seat 31 upon which the valve 37 of the cylinder and piston device 35, 36 may seat.

The lower end of the valve housing 20 is applied on the conical seat 6 at the lower end of the closed tubing string 4, in position directly above the liquid displacement receptacle 5, a lead ring 10 being interposed. On the full weight of the casing 9, enclosing the valve mechanism of the gas-lift displacement device being applied on the lead sealing ring 10, an effective seal is made between the receptacle 5 and the annular pressure-gas space or receptacle 13.

The casing 9 is provided with a pilot-valve housing 32, integral with which is a downwardly depending cylinder 34 which accommodates a close fitting sliding piston 35. A piston rod 36 is connected to the piston 35 and carries at its lower end the mushroom valve 37, which is adapted to be applied upon the seat 31 and to close the valve passage 18.

In the upper part of the cylinder 34, a concentric bore-hole 16 is provided which can be sealed off by the conical pilot valve 15 hereinafter referred to. A small transverse orifice 38 establishes communication between the bore-hole 16 and the casing 9.

The pilot-valve housing 32 is shown diagrammatically in Figure 2 as integrally formed with the casing 9 and with an upward extension 39 which is divided into a lower compartment 40 and an upper compartment 41. The lower compartment 40 communicates with the annular pressure-gas space or receptacle 13 through a radial port 48 in the pilot valve body 32, and contains a metal bellows 42 to the lower part of which the stem 43 of the pilot-valve 15 is secured. The metal bellows 42 is hermetically secured at its upper end to the partition 39a, which divides the compartments 40 and 41, and at the lower end the bellows is hermetically secured upon a base block 44, carried upon the pilot-valve stem 43 by a collar and gland nut 51. When the bellows 42 is compressed, the pilot-valve stem 43 can freely move through the opening 45 in the partition 39a between compartments 40 and 41. At the lower end of the stem 43 the pilot-valve 15 is mounted, which shuts off any flow of gas through the bore-hole 16 when sufficient pressure is applied by means of the compression spring 46 in the compartment 41. The spring 46 abuts on the disc 47 mounted at the upper end of the pilot-valve stem 43, and the pressure applied by the spring may be adjusted by the adjusting screw 49. The screw 49 is packed off gas-tight by means of the stuffing box 50, so that no gas or liquid can enter the compartment 41.

In operation pressure-gas from the gas supply system 12 (Figure 1) is admitted through a simple needle or timing valve 14 into the annular space 13 between the tubing string 4 and the casing 9 and rising main 8. This gas cannot escape because the annular pressure-gas space or receptacle 13 is sealed off at the bottom of the casing 9 by the lead sealing ring 10 on the tapered seat 6, the valves 17 and 15 being in the closed position (Figure 2). Consequently gas pressure gradually builds up in the annular space 13. At the same time this pressure is transmitted

through the radial port 28 on to the mushroom valve 17, forcing this valve firmly against its seat 27 (Figure 2). Pressure-gas is also transmitted through the radial port 48 into the compartment 40 and on to the metal bellows 42 and the pilot-valve 15. As the area of the metal bellows 42 is larger than the area of the orifice 16, which is closed by the pilot-valve 15, the gas pressure tends to compress the metal bellows 42 and raises

the pilot-valve 15 off its seat. This tendency however is opposed by the pressure of the spring 46.

When a determined pressure has been reached, that may be controlled by the adjustment of the spring 46, the valve 15 being a differential valve, suddenly rises from its seat and gas flows through the orifice 16 into the cylinder 34. The pressure is now transmitted to the top of the piston 35, which is forced downward, and the valve 37 makes contact with the valve stem 21 opens the pressure-gas inlet valve 17. The area of the piston 35 being greater than the area shut off by the valve 17, the latter is forced off its seat 21. At the same time the valve 37 is forced on to its seat 31 and prevents gas flowing from the annular space 13, entering the inner space 9c by way of the bore 18. Gas is therefore compelled to flow through the port 29 into the upper end of the liquid displacement receptacle 5, thereby forcing the liquid which has accumulated in the chamber 5, through the depending eduction pipe 11, the eduction conduit 30, the eduction ports 33 and through the rising main 8 to the surface gas/liquid collecting system or other delivery point above.

As the rate of flow from the pressure-gas annular space or receptacle 13 through the valve 17 and the ports 18 and 29 into the chamber 5 is much greater than the rate of flow from the pressure gas supply system 12 through the adjustable flow or timing valve 14, a drop in pressure in the annular pressure-gas space or receptacle 13 follows. Simultaneously with the pressure drop in the annular pressure-gas space or receptacle 13 the pressure below the metal bellows 42 and upon the piston 35 falls. On a determined pressure drop, depending on the diameter of the orifice 16, the pilot valve 15 returns to its seat in the orifice 16, under pressure of the spring 46. When the pilot valve 15 is properly seated, no further gas is supplied above the piston 35, and the gas which still exerts pressure upon the piston 35, exhausts through the small orifice 38 into the casing 9, until the pressure in the casing 9 and upon the piston 35 are equalised.

The pressure of the spring 26 and the kinetic energy of the gas flowing through the bore 18 overcome the gas pressure on the piston 35, which is equal to the pressure in the casing 9, and the valve 17 returns to its seat 21, forcing the piston 35 into its upper position and closing the supply of gas to the liquid displacement receptacle 5. The gas in the liquid displacement receptacle 5 and rising main 8 further expands and forces the "slug" of liquid in the rising main 8 to the surface.

As no gas now passes from the annular pressure-gas space or receptacle 13, the gas flowing through the adjustable timing valve 14 again builds up pressure in the annular space 13 to a maximum operating pressure, and the described cycle is repeated.

It follows that the number of operations or cycles per hour, or per day depend on the rate of flow through the adjustable timing valve 14, and therefore the number of operations per day can be regulated by reducing or increasing the flow of gas through valve 14. The number of operations per day depend on the quantity of liquid produced by the source of supply or the oil well, and by the quantity of liquid which can be raised by the quantity of gas supplied from the annular pressure-gas space or receptacle 13 for the pressure drop for which the device has been regulated.

After the liquid has been removed from the liquid displacement receptacle 5 and has reached the surface or delivery point above, a certain quantity of gas still remains in the receptacle 5, and also gas might enter the receptacle 5 from the source of supply or the oil well through the check-valve 7. If no precautions are taken this gas might create a gas-lock in the receptacle 5 and prevent or obstruct the inflow of liquid from the well into the receptacle 5. To avoid such a gas-lock being created in the chamber 5, the gas present in, or entering, the receptacle 5 is exhausted into the communicating chambers 9c and 9d of the casing 9, forming the lower part of the rising main 8 and thence into the rising main 8 through the port 29, the bore 18 and the orifice uncovered by the valve 37. This valve 37 rises from its seat 31 directly the valve 17 returns to its closed position. The pressures in the rising main 8 and liquid displacement receptacle 5 are therefore equalised at whatever pressure is maintained in the gas/liquid collecting system.

It will be understood that during the gas-lift pumping operations, pressure-gas is exhausted from the annular pressure-gas space or receptacle 13 only, and no appreciable increase in flow takes place through timing valve 14 during this period. The pressure in the gas supply system 12 is consequently not affected to any extent and the use of large capacity gas supply lines and gas reservoirs or "capacity headers" is avoided.

Furthermore in case of small producing or "stripper" wells, gas can be supplied from the casing heads of producing wells, yielding small quantities of gas against a back pressure, without affecting the back-pressure conditions of the well supplying the gas. Full use may therefore be made of the energy of the gas which otherwise would be lost in the gas collection pipe-line system.

The gas volume exhausted from the pressure-gas space or receptacle 13 at each operation is constant for any given operating condition, and is not affected by the interval between operations.

45 The intervals can be regulated by the valve 14 until the optimum condition is reached, that is the maximum quantity of liquid which can be raised by the volume of gas exhausted from the annular pressure-gas space or receptacle 13 is attained.

As the pressure in the gas supply system 12 is not influenced to any appreciable extent during the period gas is admitted into the liquid displacement receptacle 5, several automatic gas-lift displacement pumps can be operated simultaneously within the capacity of the source of gas supply, without danger of interference, or of wells going off production.

60 Timing devices or control stations which might get out of order, or cause production losses are thus unnecessary, the operating cycles being regulated by a simple needle valve.

In the constructional form of the apparatus illustrated in Figures 3a, 3b and 3c, the rising main 8 (Figure 3a) is connected by the screw-threaded tubular fitting 9a with the upper part of the casing 9 serving as the lower part of the rising main 8, which in these figures for convenience of illustration is shown in three separated parts, namely the upper part in Figure 3a, the middle part in Figure 3b, and the lower part in Figure 3c, respectively separated on the lines a—a, and b—b as indicated in those figures, at positions similarly denoted by the lines a—a and b—b in the diagrammatic section of Figure 2, the casing 9 being

formed of connected lengths of pipe sections, the lowermost section being connected to the housing 20 of the main gas-inlet valve 17; while the housing 20 at its lower end is adapted for the screw-threaded connection of the supporting ring 20c (Figure 3c), which has an external conical shape at its lower end for accommodation within a corresponding internal conical seat in the internally screw-threaded coupling sleeve 4a. The sleeve 4a at its upper end is applied upon the reduced lower externally screw-threaded end of the tubing 4 serving as the external wall of the pressure-gas space or receptacle 13, and at the lower end the tubing is adapted for the connection of the coupling sleeve 4a for the suspension of the liquid displacement receptacle 5, through which extends downwardly the eduction pipe 11 to a position near the bottom of the receptacle, a lead ring 10 being interposed between the ring 20c and the conical seat in the coupling sleeve 4a.

The apparatus illustrated in Figures 3a, 3b and 3c comprises the pilot valve 15 and equipment (Figures 3a and 3b) mounted concentrically within the upper part of the casing 9 serving as the lower part of the rising main, and the main gas-inlet valve 17 and equipment (Figures 3b and 3c), the gas-inlet valve 17 being mounted concentrically within a seating sleeve 18a (Figures 3b, 3c and 10), set within the main gas-inlet valve housing 20 (Figures 3b and 3c).

The respective pilot valve 15 and main gas-inlet valve 17 as illustrated in Figures 3a and 3b and 3c are supported in a construction many of whose parts are correspondingly numbered with equivalent parts indicated in Figures 1 and 2. Thus in those figures the helical spring 46 and bellows 42 and the pilot valve 15 are respectively mounted within the tubular housings 41 and 40, the housing 41 serving to enclose the helical spring 46 and piston 47, and the housing 40 serving to enclose the bellows 42.

The bellows 42 is advantageously provided in known manner of corrugated longitudinal section and formed of alternate ridges and furrows of circular shape from thin metal having an elastic characteristic.

The tubular housing 41 (Figure 3a) has applied at its upper end a screw-threaded socket fitting 58, through which passes the adjusting screw-threaded spindle 49, that extends into the housing 41 for variation of the compression applied to the enclosed helical spring 46. The upper cylindrical part of the adjusting screw-threaded spindle 49 extends through a stuffing box 58a to engage a contact plate applied upon the upper end of the helical spring 46, and the lower end of the helical spring abuts upon the top face of the piston 47, that is mounted upon the upper end of the pilot valve spindle 43 and is adapted to slide within the tubular housing 41.

The housings 40 and 41 are connected together in vertical alignment by the externally screw-threaded bush 40a, in which an axial hole is provided through which extends the pilot valve spindle 43. An internally screw-threaded socket fitting 40b is applied upon and beneath the lower reduced and externally screw-threaded part of the bush 40a, and the latter is packed to ensure fluid tightness. The underface of the socket fitting 40b has the upper end of the bellows 42 hermetically secured to it, and at the lower end the bellows is similarly secured to a cylindrical base block 44, carried upon the pilot valve spindle 43 by a collar secured upon the spindle and a gland nut 51.

The assembly comprising the tubular housings 40 and 41 (Figures 3a and 3b) is supported upon a bush 52, that is externally screw-threaded at its ends respectively for engagement with an internal screw-thread at the lower end of the housing 40 and at the upper end of the pilot valve housing 32 whereby the latter is connected to the lower end of the tubular housing 40; the bush 52 having an axial bore through which the pilot valve spindle 43 of smaller diameter than the axial bore, may freely pass, and through which also the pressure gas is accessible to the housing 40 from below.

The pilot valve housing 32 is also screw-threaded externally at its respective ends, for the connection of adjacent lengths of the casing 9, and is provided with a radial port 48 for admission of the pressure gas from the annular pressure-gas space or receptacle 13 within the surrounding tubular casing 4; the pressure gas being accessible from the central cavity or bore 40c in the pilot valve housing 32, through the axial bore in the bush 52 to the housing 40 within which the bellows 42 is enclosed. Thus the bellows 42 is rendered subject to the pressure prevailing in the annular pressure-gas space or receptacle 13.

The pilot valve housing 32 (Figures 3b, 11 and 12) is also provided with three vertical through-way passages 33, to permit of the free upward passage therethrough of the liquid from the liquid displacement receptacle 5 and the pressure gas by which it is raised.

The pressure gas derived from the pressure-gas space or receptacle 13, acting on the piston 35 passes through the radial port 48 into the centrally disposed bore or valve chamber 40c, and is thus accessible externally of the bellows 42 above, whereby the latter is contracted and the pilot valve 15 thus raised from its seat on the pressure rising above the opposed pressure of the helical spring 46. The liquid under the pressure of the pressure gas flows through the passages 33 and thence through the annular spaces between the housings 40, 41 and the casing 9 into the rising main 8.

The pilot valve 15 has at its lower end a conical face whereby it is adapted to seat upon the upper end of a nipple 53 having a central bore of small diameter, the nipple being centrally secured upon a bush 54 having a central bore 16 of a diameter greater than the bore of the nipple above it, and a radial bore-hole 38 extending outward from the central bore 16, open to the casing 9. The bore-hole 38 is advantageously of larger diameter at the outer part of its length. The bush 54 is externally screw-threaded at its upper and lower ends respectively to enter the internally screw-threaded lower end of the central bore of the pilot valve housing 32, and the internally screw-threaded upper end of the cylinder 34.

Within the cylinder 34 a piston 35 is adapted to slide having a downwardly extending piston rod 36, at the lower end of which a mushroom valve 37 is mounted, that in its lower position is adapted to close upon the seat 31 formed at the upper end of the seating sleeve 18a of the main gas-inlet valve 17, and to contact and to depress the upper stem 17a of the valve 17, whereby the valve 17 is opened against the action of the helical spring 26 (Figure 3c). Thus on the opening of the pilot valve 15, the pressure gas passes downward through the nipple 53 and into the cylinder 34, whereupon the piston 35 descends, carrying with it the valve 37, whereby the upper stem 17a, and the valve 17 (Figure 3c) descend

against the action of the helical spring 26, and against the pressure gas admitted through the port 28.

The cylinder 34 (Figure 3b) at its lower end is internally screw-threaded for the reception of the externally screw-threaded upper end of a tubular fitting 55, having in a mid position in its length an outwardly extending circular flange that contacts with the lower end of the cylinder 34, and having a downwardly extending cylindrical part adapted to have a sliding fit within the upper end of the tubular part 56 that is adapted for the enclosure of the mushroom valve 31 mounted at the lower end of the piston rod 36. By such means the adjacent ends of the parts 34 and 56 are held together and maintained in alignment without connection.

The part 56 is screw-threaded internally at its lower part and secured at its lower end upon the upper externally screw-threaded end of the seating sleeve 18a of the main gas-inlet valve 17 (Figures 3b and 10), the part 56 being also open to the casing or eduction pipe 9 through the ports 56a, whereby the underside of the piston 35 is subject to the pressure there prevailing.

The valve seating sleeve 18a of the main gas-inlet valve 17 (Figures 3c and 10) is provided beneath the head 18b, with an external screw thread, whereby the sleeve 18a may be secured within the central cavity in the upper part of the main gas-inlet valve housing 20 (Figures 3b, 3c and 4 to 9); and at its lower end the valve seating sleeve 18a is reduced in diameter and provided with radial holes 18c, whereby a perforated wall is provided affording communication between the annular port 18d and the passage 18, while an external shoulder 18e is provided near the lower end of the seating sleeve adapted to fit upon the internal shoulder 20d beneath in the valve housing 20 (Figure 3c).

In the main gas-inlet valve housing 20 three vertical ports 30, 29 and 30 are provided of arcuate form in transverse cross-section (Figures 4 to 9), and a radial port 28 (Figures 3c, 6 to 9). The ports 30 serve for the upward passage of the liquid from the eduction pipe 11 into the eduction pipe 9. The ports 30 unite at a position 20b (Figure 3c), immediately above the upper end of the eduction pipe 11, and beneath the bottom guide block 20e for the lower valve stem 17b. In the guide block 20e a central bore is provided, for the accommodation of the lower stem 17b of the valve. The central bore at the lower end communicates with the lower ends of a number of holes of smaller diameter spaced apart in the guide block, to extend upward to the top face thereof in order to ensure freedom of movement of the valve in case of any liquid accumulation in the lower part of the central bore.

The valve 17 (Figure 3c) may be inserted into position upon removal of the guide block 20e, and the helical spring 26 may be applied upon the lower valve stem 17b, and be held in position by the guide block.

The valve 17 may be adapted at its upper end to be guided in its vertical movements as by the radially or diametrically extending parts 22 (Figure 3b).

The port 29 is the gas-inlet port into the upper part of the liquid displacement receptacle 5, and terminates at the inlet side in the annular recess opposite to the radial holes 18c (Figure 3c). The radial port 28 serves on opening of the valve 17, for the admission of the pressure gas from the annular space 13 through the passage 18, port

entrance 29a and port 29 into the liquid displacement receptacle 5.

The oppositely disposed lateral ports 30 of arcuate cross-section are at the lower ends directly accessible to the eduction pipe 11 (Figures 3c, 8 and 9) that extends to the lower part of the liquid displacement receptacle 5, the latter being at its lower end provided (as illustrated in Figure 1) with a non-return valve 7.

10 The operation of the apparatus illustrated in Figures 3a to 12 is substantially the same as the apparatus diagrammatically shown in Figures 1 and 2.

15 Thus after the pressure gas has reached its maximum operating pressure in the annular space or receptacle 13 the main gas-inlet valve 17 is opened on the operation of the pilot valve 15 and piston 35. The high pressure gas then flows into the liquid displacement receptacle 5 and pressure is thus applied on the liquid that has accumulated in that receptacle. As the liquid can only escape from the chamber 5 through the eduction tube 11, the liquid rises in the tube. On the liquid reaching the top of the tube 11 the liquid column divides into two columns on entering the ports 20b and then rises through both passages 30 into the annular space between the tubular enclosure 56, cylinder 34 and the lower part of the casing 8. The liquid thereupon rises 20 through the passages 33 in the pilot valve housing 32 and enters the annular space between the casings 40 and 41 and the upper part of the casing 9. The liquid continues to flow through this annular space between bushing 40a, casing 39, 25 stuning box 50a and eduction casing 9, until it reaches the eduction rising main 8.

30 The quantity of gas passing from the annular pressure-gas space 13 into the liquid displacement receptacle 5 and the rising main 8 should be sufficient to bring the "slug" or column of liquid to the surface at the delivery point. The quantity of gas should be approximately equivalent to the capacity of the receptacle 5, plus the capacity of the rising main 8, and should be at a final pressure when the top of the "slug" or column of liquid reaches the surface, equivalent to the hydrostatic pressure of the "slug" or column of liquid in the rising main 8.

35 The operation of the apparatus illustrated in Figures 3a, 3b and 3c is hereinafter described by way of example, and approximate figures are given which are illustrative of the conditions that may be employed, and involve no limitation.

40 If for example the maximum operating pressure in the annular space 13 is 250 lbs./square inch and the length of the column of liquid of specific gravity 0.85, is 227 feet, the internal diameter of the rising main 8 is 1½ inches, the depth of the oil well is 2,100 feet and the capacity 45 of the liquid displacement receptacle 5 is 5 cubic feet, the required quantity of pressure gas and the pressure drop in the annular pressure-gas space or receptacle 13 to bring the "slug" or column of liquid to the surface are readily calculated.

45 As the pressure drop in the annular space 13 is dependent on the mean area of the bellows, and the area of the orifice closed by the pilot valve 15, the diameter of the orifice 38 to be inserted into the bush 54 may be readily determined.

50 The port 48 serves to establish communication between the annular pressure-gas or receptacle 13, and the central cylindrical cavity 40c in the pilot valve housing or enclosure 32. The pres-

sure gas which enters through the port 48 from the annular pressure-gas space or receptacle 13 exerts a pressure on the bellows 42 and the pilot valve 15. This pressure is static until the maximum operating pressure has been reached in the annular pressure-gas space or receptacle 13. When this pressure has been reached the pilot valve 15 opens, and a small quantity of pressure gas flows through the bore 16 into the cylinder 34 upon the piston 35. The piston is forced downward and the main gas-inlet valve 17 is opened. As the cylinder 34 has only one outlet 38, of small diameter (about $\frac{1}{2}$ inch) the gas flow which takes place through the bore 48 after the valve 15 has opened, is equivalent to the amount of gas which can flow through orifice 38 at the pressure in the annular space 13. This amount is extremely small and is approximately 3 cubic feet per minute at a pressure of 200 lbs./square inch. It is therefore only necessary that the port 48 be slightly larger than the diameter of the orifice 38 and a diameter of $\frac{1}{8}$ inch is more than necessary.

The port 48 serves to establish communication between the annular space 13 and the space below the main gas-inlet valve 17 (after the main gas-inlet valve 17 has been opened) through ports 29a and 29 with the liquid displacement receptacle 5.

As the gas flowing from the annular pressure-gas space or receptacle 13 into chamber 5 must force the liquid to the surface or delivery point in a fairly short space of time, depending on the required velocity of the "slug" or column of liquid in the rising main 8, it is desirable to keep the friction losses due to restricted gas passages, as low as possible. For this purpose the port 28 (Figures 3c, 8 and 9) must be made as large as is practically possible; this also applies to the perforated grid wall 18c and the ports 29a and 29 (Figures 3c, 6, 7 and 10).

Before the apparatus is passed into the oil well it is first decided whether to produce the liquid by raising a fairly large quantity of liquid per "shot" at long intervals, or a small quantity per "shot" at short intervals between "shots." Whether large or small quantities of liquid are to be raised per "shot" does not make any difference to the ultimate quantity of gas required to raise the same quantity of total liquid per day. Thus, if for example 40 gallons of liquid require 400 cubic feet of gas to raise this liquid to the delivery point, 20 gallons of liquid will require only 200 cubic feet of gas. In the first case the pressure drop in the annular space 13 must be greater, because 400 cubic feet are required per "shot," whereas in the latter case the quantity passing from the annular pressure-gas space or receptacle 13 is 200 cubic feet per "shot" only, and consequently the pressure drop in the annular space 13 is appreciably less. The overall input gas to liquid ratio in both cases is the same, namely $400/40$ or $200/20 = 10$ cubic feet gas to 1 gallon of liquid. Therefore, if the capacity of the oil well be 4,000 gallons of liquid per day, the quantity of gas required when the well is producing at the rate of 40 gallons per "shot" would be $4,000/40 \times 400$ cubic feet of gas, or 40,000 cubic feet of gas; whereas if this quantity of liquid were produced at the rate of 20 gallons per "shot," the required amount of gas would be $4,000/20 \times 200$ cubic feet of gas, or 40,000 cubic feet of gas, which quantities are identical.

When the operating pressure and quantity of liquid to be raised per "shot" has been decided

upon, the pressure drop in the annular space 13 is calculated for the quantity of gas passing from the annular space 13 into the receptacle 5 to raise this liquid to the surface or delivery point. The apparatus is then adjusted for this pressure drop before it is passed into the oil well.

After the apparatus has been passed into the well, and properly seated on the tapered seating with the lead ring 10 interposed, the needle valve 14 is fully opened, and gas admitted into the annular pressure-gas space or receptacle 13. When the operating pressure to which the apparatus has been adjusted has been reached, the pilot valve 15 opens, and the pressure gas flows into the cylinder 34, the piston 35 thus forced being downward. After the valve 37 makes contact with the valve stem 21, the main gas-inlet valve 17 opens, and the valve 37 is seated upon the seating 31, and the pressure gas from the annular pressure-gas space or receptacle 13 flows into the liquid displacement receptacle 5, whereby the liquid that has collected in this receptacle is forced upward to the delivery point.

When the pressure drop for which the apparatus has been adjusted has taken place in the annular pressure-gas space or receptacle 13, the pilot valve 15 closes and the valve 17 again closes, and no further gas is supplied to the liquid displacement receptacle 5, until the operating pressure has again been reached in the annular pressure-gas space or receptacle 13.

As the timing valve 14 is fully open, the time to replenish the annular pressure-gas space or receptacle 13 is comparatively short, and if this valve were left fully open, the liquid in the well would soon be exhausted, and only small quantities of liquid would be raised with the constant quantities of pressure gas passing from the annular pressure-gas space or receptacle 13. Consequently the pressure gas to liquid ratio would increase to above the normal quantity of gas required per gallon of liquid. As this is undesirable, the timing valve 14 is gradually or partially closed whereby the interval between "shots" is prolonged. This partial closure of the needle valve 14 is continued until the quantity of liquid which is raised to the delivery point per "shot" is approximately the theoretical quantity which can be raised by the volume of gas passing from the annular pressure-gas space or receptacle 13. When this condition has been reached the timing or needle valve 14 is left in that position, and the apparatus now continues to operate automatically, raising each time the maximum quantity of liquid possible for the volume of pressure gas injected into the chamber 5.

As the pressure drop in the annular pressure-gas space or receptacle 13 is the same for each "shot," and as the capacity of this annular space is constant, it follows that the quantity of pressure gas derived from the annular space 13 is always the same, and consequently the volume of pressure gas necessary per gallon of liquid raised to the surface is always the same for any given operating condition.

Thus for a given operating condition the volume of pressure gas passing from the annular pressure-gas space or receptacle 13 is always constant, as long as the gas pressure in the gas supply lines is higher than the operating pressure of the apparatus. Thus the pressure in the annular pressure-gas space or receptacle 13 cannot build up to a pressure higher than the operating pressure of the apparatus.

Assuming that at an opening pressure of 250

lbs./square inch, and a closing pressure of 200 lbs./square inch, 200 cubic feet of gas passes from the annular space 13 into the liquid displacement receptacle 5 to raise 20 gallons of liquid to the delivery point, and that this quantity of liquid is raised at intervals of one hour, the average rate of flow at which the gas flows through the timing or needle valve 14 is then 200₆₀, or 3.33 cubic feet per minute.

When the pressure in the annular pressure-gas space or receptacle 13 is 200 lbs./square inch, that is when the valve 15 closes, and no further pressure gas is admitted into the liquid displacement receptacle 5, the rate of flow through the timing valve 14 is slightly higher than when the pressure reaches 250 lbs./square inch in the annular pressure-gas space or receptacle 13. This is due to the increased differential between the up-stream and down-stream side of the needle valve 14. This difference in flow rate is so small that the pressure drop due to this increased flow rate cannot be measured with an ordinary pressure gauge connected in the gas supply line near the timing valve 14. This very small pressure drop during the "on" period permits of the use of gas supply pipes of small diameter, so that large diameter pipes which are commonly used to reduce the pressure drop in the supply pipes, when other types of displacement pumps are used, are unnecessary.

In the example hereinbefore described, the flow rate through the timing valve 14 is 3.33 cubic feet of gas per minute, and the interval between the "on" period or "shots" is one hour. By increasing the flow rate from 3.33 to 4 cubic feet per minute on slightly opening the needle valve 14, the interval between "shots" becomes $3.33/4 \times 60$ or 50 minutes. In the first case the number of "shots" per day would be 1,440₅₀ minutes or 24 "shots," and in the latter case 1,440₅₀ minutes or 28.8 "shots" per 24 hours. If on the other hand the rate of flow were decreased to 2 cubic feet per minute the number of "shots" per day would be

$$\begin{array}{r} 1,440 \\ - 3.34 \\ \hline 2 \end{array}$$

or 14.4 "shots" per day.

Thus by increasing or decreasing the average rate of flow through the timing valve 14, the number of "shots" or "on" periods per day can be regulated without the use of any elaborate timing device.

I claim:

1. A gas-lift pumping apparatus for periodically raising from an outside source to an elevated delivery point successive charges of liquid first admitted within a closed liquid displacement receptacle, consisting in combination of a liquid displacement receptacle, a pressure-gas receptacle disposed above said liquid displacement receptacle, means for the admission of pressure-gas to said pressure-gas receptacle whereby the determined operating pressure is there attained, an inner casing within said pressure-gas receptacle, a pressure-gas inlet valve housing at the lower part of said inner casing, said housing having a vertical passage-way, a pressure-gas inlet valve normally closed under upward spring pressure, and mounted within said passage-way, a radial port in said housing extending from said pressure-gas receptacle to a cavity in said housing beneath said pressure-gas inlet valve, a pressure-gas inlet port extend-

ing upward in the said housing from its lower face and communicating with said vertical passage-way at a position immediately above said pressure-gas inlet valve, an outlet port for the liquid raised from the said liquid displacement receptacle, extending from top to bottom of said housing, an eduction pipe depending from said housing into said liquid displacement receptacle to the lower part thereof, and communicating with said outlet port, and automatic means mounted within said inner casing adapted under the determined operating pressure of the pressure-gas, comprising a pilot valve and a cylinder piston and valve device, whereby the pilot valve is opened to admit the pressure-gas into the cylinder of said cylinder, piston and valve device, whereupon the valve of said cylinder, piston and valve device descends and opens the pressure-gas inlet valve, and closes said vertical passage-way at the upper end, pressure-gas being thus admitted to the upper end of the liquid displacement receptacle, the liquid discharged from the liquid displacement receptacle passing upwardly through the eduction pipe, and thence through the inner casing and the rising main to the delivery point, the valve of said cylinder, piston and valve device being raised from its seat on the closure of said pressure-gas inlet valve, at the conclusion of each operational cycle and pressure-gas receptacle re-charged with pressure-gas and the liquid displacement receptacle with liquid.

2. A gas-lift pumping apparatus as specified in claim 1 in which a central axial bore-hole is disposed at the upper end of the cylinder, piston and valve device, which is sealed off by the pilot valve at the end of each cycle, and a small transverse radial passage disposed between the central axial bore-hole and the external wall of the cylinder at its upper end, communicating between the central axial bore-hole, and the inner casing, whereby on the closure of the pilot valve at the end of a cycle, the gas remaining in the said cylinder exhausts through the said transverse radial passage into the lower part of said inner casing until the pressures in the inner casing and upon the said piston are equalised.

3. A gas-lift pumping apparatus as specified in claim 1, in which the pilot valve equipment comprises a smaller casing disposed lengthwise within the inner casing, the smaller casing being divided by a transverse annular partition into an upper and a lower compartment, the latter communicating with the pressure-gas receptacle through a radial port, an expansion spring disposed lengthwise in the upper compartment and adapted normally to apply slight axial pressure upon the upper end of the stem of the pilot valve for its closure, a metal bellows within said lower compartment corrugated in its length in alternate annular ridges and furrows and being thus adapted for lengthwise contraction under the determined operational pressure of the pressure-gas, the respective upper and lower ends of said metal bellows being hermetically secured to said transverse annular partition at the upper end, and to a base part mounted near the lower end of the pilot valve stem, whereby on the endwise contraction of the metal bellows at the determined operational pressure, the pilot valve is adapted to open and to rise from its seat against the downward axial pressure applied by said expansion spring.

4. A gas-lift pumping apparatus for periodi-

cally raising from an outside source to an elevated delivery point successive charges of liquid first admitted within a closed liquid displacement receptacle, consisting in combination of a liquid displacement receptacle, a pressure-gas receptacle disposed above said liquid displacement receptacle and formed by and between an external casing closed at its upper end, and an inner casing serving as the lower part of the rising main and extending upward through the external casing and thence to the delivery point, and automatic means mounted within said inner casing adapted under the determined operating pressure of the pressure-gas, comprising a pilot valve and a cylinder piston and valve device, whereby the pilot valve is opened to admit the pressure-gas into the cylinder of said cylinder, piston and valve device, whereupon the valve of said cylinder, piston and valve device descends and opens the pressure-gas inlet valve, and closes said vertical passage-way at the upper end, pressure-gas being thus admitted to the upper end of the liquid displacement receptacle, the liquid discharged from the liquid displacement receptacle passing upwardly through the eduction pipe, and thence through the inner casing and the rising main to the delivery point, the valve of said cylinder, piston and valve device being raised from its seat on the closure of said pressure-gas inlet valve, at the conclusion of each operational cycle and pressure-gas receptacle recharged with pressure-gas and the liquid displacement receptacle with liquid.

5. A gas-lift pumping apparatus as specified in claim 1, in which the pilot valve stem is extended upward into the upper compartment of the smaller casing in the lower compartment of which the metal bellows is mounted, in which an expansion spring is interposed between an abutment plate mounted on the upwardly extending end of the pilot valve stem, and an abutment plate mounted on the upper end of said expansion spring, and a screw mounted at the upper end of said smaller casing, adapted for contacting at its lower end the upper abutment plate as means for the adjustment of the pressure applied to said expansion spring.

6. A gas-lift pumping apparatus as specified in claim 1, in which the expansion spring, the metal bellows, the pilot valve, the cylinder piston and valve device and the pressure-gas inlet valve and its housing are mounted in their order in alignment within tubular parts connected together by tubular connecting parts that accommodate the respective valve stems, and in which the connected tubular parts are mounted and supported within a surrounding tubular inner casing forming an annular space surrounding said connected tubular parts, that at the upper end discharges into the rising main, while at the lower end the said inner casing serves for the suspension of

the eduction pipe that extends downward into the lower end of the liquid displacement receptacle.

7. A gas lift pumping apparatus as specified in claim 1, in which the pilot valve equipment comprises a smaller casing disposed lengthwise within the inner casing, the smaller casing being divided by a transverse annular partition into an upper and a lower compartment, the latter communicating with the pressure-gas receptacle through a radial port, an expansion spring disposed lengthwise in the upper compartment and adapted normally to apply slight axial pressure upon the upper end of the pilot valve for its closure, a metal bellows within said lower compartment corrugated in its length in alternate annular ridges and furrows and being thus adapted for lengthwise contraction under the determined operational pressure of the pressure-gas, the respective upper and lower ends of said metal bellows being hermetically secured to said transverse annular partition at the upper end, and a base part mounted near the lower end of the pilot valve stem, whereby on the endwise contraction of the metal bellows at the determined operational pressure, the pilot valve is adapted to open and to rise from its seat against the downward axial pressure applied by said expansion spring, and means for adjustment of the pressure applied by the expansion spring upon the stem of the pilot valve, consisting of an adjustable screw passing centrally through the upper end of the smaller casing, the said screw abutting at its lower end against a contact plate secured at the upper end of said expansion spring, the lower end of the expansion spring engaging the contact plate upon the upper end of the pilot valve stem.

8. A gas lift pumping apparatus as specified in claim 1, in which the expansion spring, the metal bellows, the pilot valve, the cylinder piston and valve device and the pressure-gas inlet valve and its housing are mounted in their order in alignment within tubular parts connected together by tubular connecting parts that accommodate the respective valve stems, and in which the connected tubular parts are mounted and supported within a surrounding tubular inner casing forming an annular space surrounding said connected tubular parts, that at the upper end discharges into the rising main, while at the lower end the said inner casing serves for the suspension of the eduction pipe that extends downwardly into the lower end of the liquid displacement receptacle, and in which the inner casing is surrounded by a cylindrical outer casing forming between the outer casing and the inner casing an annular space serving as pressure-gas receptacle, at the lower end of which the liquid displacement receptacle is suspended.

JAN LAMBERTUS BENARD.
